UNITED STATES PATENT OFFICE.

FRITZ BALZER, OF MOLINE, ILLINOIS, ASSIGNOR TO TROY LAUNDRY MACHINERY CO., LTD., OF CHICAGO, ILLINOIS, A CORPORATION OF NEW YORK.

CYLINDER CONSTRUCTION.

Application filed November 14, 1923. Serial No. 674,633.

The present invention relates to cylinder construction.

More particularly, the present invention relates to rotary cylinders such as are used in washing machines. It is common practice to build washing machines with an outer shell or casing which encloses a rotary cylinder, which cylinder contains the goods to be washed. Such cylinders are ordinarily provided with baffles located on the inside of said cylinders, which baffles perform the function of tumbling the goods about as the cylinder is rotated.

An object of the present invention is to provide a washing machine cylinder which may be made of a minimum of parts and which will have improved sturdiness over cylinders as now known and used.

A further object is to provide a cylinder construction in which the baffles above referred to cooperate with the remaining parts of the cylinder to provide a very sturdy structure.

A further object of the present invention is to provide a cylinder which is cheap to manufacture, sturdy in construction, and which contains a minimum of parts.

Further objects will appear as the description proceeds.

30 Referring to the drawings—

Figure 1 is a view in side elevation of a washing machine cylinder.

Figure 2 is a sectional view taken along the plane indicated by the arrows 2—2 of Figure 1.

Figure 3 is a sectional view taken along the plane indicated by the arrows 3—3, which arrows appear in Figures 1 and 2.

Figure 4 is a sectional view taken along the plane indicated by the arrows 4—4 of Figure 2; and

Figure 5 is a sectional view taken along the plane indicated by the arrows 5—5 of Figure 1.

45 The numeral 1 indicates as a whole a washing machine cylinder provided with trunnions 2, 2, at the ends thereof. Said trunnions are mounted in bearings, not shown, and in operation the cylinder 1 will be rotatably mounted within an enclosing casing, not shown. Said trunnions 2, 2, are part of or united to the end walls 3, 3, of the cylinder.

According to the illustrated embodiment of the present invention, the cylinder 1 is

provided with a strengthening transverse partition 4 midway of its length. The end walls 3, 3, are provided with abutment means or bosses 5, 5, disposed near the periphery of said members 3, 3. The conformation of said bosses, as viewed longitudinally of the cylinder 1, may be described as being generally V-shaped but with the apex rounded. Said rounded apex will be disposed towards the axis of its corresponding member 3, 3, while the base of said V-shaped member will be disposed at or near the periphery of its corresponding member 3, 3. The bosses 5, 5, of one end wall 3 are disposed in longitudinal alignment with and are of substantially the same configuration as the bosses on the opposite end wall. Said bosses provide supporting means for the sheet metal members 6, 6, which members provide a cylindrical wall for the cylinder 1.

Each of the sheet metal members 6, 6, is provided with a bowed portion near one of its circumferential extremities, which bowed portion is indicated by the numeral 7. Each member 6 (except one, as indicated, which is cut away to provide an opening for a door) also comprises an extended portion 8 which is of arcuate form having its arcuate axis coincident with the axis of rotation of the trunnions 2, 2, and which is provided with a plurality of apertures for the ingress and egress of washing medium. The bowed portion 7 of each of the members 6, 6, conforms to the outline of a corresponding pair of bosses 5, 5. Said bowed portion of each member 6 may be connected to the end walls 3, 3, and a partition 4 by means of angles 9, which angles may be secured by rivets or other preferred fastening means. The grooves provided by the bowed portions 7, 7, of the members 6, 6, may be covered by plates 10, 10, whereby said bowed portions will not form objectionable pockets. The partition 4 will be cut away to afford space for the bowed portions 7, 7, of the sheet metal members 6, 6, said portions 7, 7, being secured to partition 4, as above noted, by the angles 9.

According to the disclosure of the present invention, two sliding doors are provided, one of said doors being located on either side of the partition 4, though the number of doors may be varied as desired. Said doors are indicated by the numerals 11, 11, the door at the right-hand side of partition 4 in

Figure 1 being shown in open position, while the door 11 at the left-hand side of the partition 4 in Figure 1 is shown in closed position. Said doors open and close with a circumferential movement, being guided in such movement by slots provided for that purpose.

It will be noted that the arcuate portions 8, 8, of the sheet metal members 6, 6, occupying the upper right and upper left portions of the cylinder, as viewed in Figure 2, have a shorter radius than do the other arcuate portions 8, 8. This construction is preferred for the purpose of providing space for the sliding doors 11, 11. Each of said doors 11, as noted above, rides in grooves located at each end of said door, certain of which grooves are indicated in Figures 3 and 4 by the numeral 11^a. The band 12 encircling the cylinder 1 provides the outer boundaries of said grooves 11^a, 11^a, while the arcuate members 12^a and 12^b provide the inner boundaries of said grooves. The groove at each end of the cylinder (see the construction at the upper left-hand portion of Figure 1) is provided by the portion 12^c of the corresponding end wall 3 and the corresponding rib mask 12^d. As noted above, the door 11 at the right-hand side of the partition 4 is shown in open position, for which reason said door 11 appears in section in Figure 3. Inasmuch as the door at the right-hand side of partition 4 is shown in open position, said door does not appear in Figure 3. For like reasons the left-hand door 11 does not appear in Figure 4, but the right-hand door 11 does appear in section in said Figure 4.

Each door 11 is of arcuate form and is provided with a pocket 13 which carries one or more locks 14. Each lock 14 is provided with a sliding bolt 15 adapted to have a movement parallel with the axis of rotation of the cylinder. Each of said bolts 15 is operated by a handle 16 which is adapted to have a rocking movement toward and away from the periphery of the cylinder 1. The bolt 15, when the door 11 is in closed position, may fit within a corresponding aperture in one of the end walls 3, 3, depending upon the location of the corresponding lock 14, whereby to hold its door 11 against opening movement. At such times that a door is open, the bolts 15, 15 thereon will not register with any aperture of sufficient depth to permit their handles 16, 16 to move to a position within the overall dimensions of the cylinder 1. By reason of this construction, the handles 16, 16 will be held in protruding position at such times that their corresponding door 11 is open, so that the cylinder 1 will not be inadvertently set in motion with the door open, inasmuch as the protruding handles 16, 16, will not permit operation of the corresponding door of the enclosing shell or casing, not shown. This

feature is not claimed in the present application, but is included in another application by the present applicant.

It will be clear without detailed explanation that when the cylinder 1 is in operation and is being rotated on the trunnions 2, 2, the goods within the cylinder will be tumbled about in contact with the inside walls of the cylinder, including the baffles provided by the bowed portions 7, 7, of the sheet metal members 6, 6. Stresses of considerable force are imposed upon said baffles, but according to the present invention such stresses are communicated directly to the bosses 5, 5, of the end walls 3, 3, and partition 4, which are well adapted to take the stresses referred to. By reason of the present invention, a minimum of parts are required, inasmuch as each of the sheet metal members 6, 6, performs the double function of providing cylinder wall construction as well as baffle construction. The members 6, 6, are rigidly united to the end walls 3, 3, and partition 4, in a simple manner so that the cost of manufacture will be reduced materially over present construction, and sturdiness will be greatly improved.

While a preferred embodiment of the present invention has been described in detail, it will be clear that many modifications will occur to those skilled in the art. It is intended in this patent to cover all such modifications which fall within the scope of the invention as defined by the appended claims.

I claim:

1. Cylinder construction comprising supporting members provided with integral aligned abutments and a plurality of sheet metal members carried by said abutments and shaped to conform to the abutments upon said supporting members, said sheet metal members comprising the cylindrical wall of said cylinder construction, each of said sheet metal members being mounted to extend from one set of abutments to and conformed over the next set of abutments.

2. Cylinder construction comprising a pair of supporting members provided with integral abutment members, the abutment members of one of said supporting members being arranged in pairs relative to the abutments of the other of said supporting members, a plurality of sheet metal sections arranged peripherally of said cylinder construction, each of said sheet metal sections having a portion conforming to said abutments and extending inwardly of said cylinder construction and extending to the next pair of abutments, and means for securing said sheet metal sections to said abutments and to said supporting members.

3. Cylinder construction comprising a plurality of sheet metal members of arcuate form, means for connecting together said

- sheet metal members to form a cylinder, a circumferentially sliding door for said cylinder, one of said sheet metal members being of less radius than the remainder of said sheet metal members to provide space for the movement of said door and guide means for said door, said connecting means comprising relatively sturdy members lying in planes substantially normal to the axis of said cylinder in construction, said sheet metal members having bowed portions extending longitudinally and radially of said cylinder, said supporting members being provided with abutment means, said bowed portions being connected to said abutment means in a position to communicate to said abutment means stresses directed circumferentially of said cylinder. 15

Signed at East Moline, Illinois, this 7th day of November, 1923.

FRITZ BALZER.
